UNITED STATES PATENT OFFICE.

ADOLPH F. GUSTAFSON, OF PUEBLO, COLORADO.

SAFE.

No. 851,744.

Specification of Letters Patent.

Patented April 30, 1907.

Application filed November 9, 1905. Serial No. 286,604.

To all whom it may concern:

Be it known that I, ADOLPH F. GUSTAFSON, a citizen of the United States, residing at Pueblo, in the county of Pueblo and State 5 of Colorado, have invented a new and useful Safe, of which the following is a specification.

This invention relates to safes, and has for its principal object to provide a novel form 10 of safe of that type in which a screw is employed for locking purposes.

A further object of the invention is to provide a safe of this character in which a screw carried by the door is adjustable to inoperative 15 position so that the door may be readily opened and closed without turning the screw.

With these and other objects in view, as will more fully hereinafter appear, the invention 20 consists in certain novel features of construction and arrangement of parts, hereinafter fully described, illustrated in the accompanying drawings, and particularly pointed out in the appended claims, it being 25 understood that various changes in the form, proportions, size and minor details of the structure may be made without departing from the spirit or sacrificing any of the advantages of the invention.

30 In the accompanying drawings:—Figure 1 is a sectional plan view of a safe constructed in accordance with the invention. Fig. 2 is an elevation of a portion of the safe showing the door in open position, a portion of the hinge being illustrated in section. Fig. 3 is a sectional plan view of a portion of the hinge. Fig. 4 is a detail sectional view of a portion of the door on the line 4—4 of Fig. 2 illustrating the manner in which the operating stem 40 of the combination-lock is mounted.

Similar numerals of reference are employed to indicate corresponding parts throughout the several figures of the drawings.

45 The body portion 10 of the safe is shown in the present instance as cylindrical in form, and is preferably made of manganese steel or the like, the cylinder resting in a horizontal position on a suitable support 11 which may 50 be formed integral with the cylinder casting if desired. Extending across the central portion of the cylinder is a cross bar or partition 12, at the center of which is a tapered opening for the reception of a tapered flange 55 13 that forms a part of a bar 14, said bar being threaded near its center for the reception

of a locking nut 15 which engages against one wall of the cross bar or partition and serves to lock the central bar 14 in proper position. This bar 14 is provided at each end 60 with female screws for the reception of threaded bolts carried by the doors.

The safe in the present instance is shown as provided with two doors 16, 16' that are disposed, respectively, at opposite ends of 65 the cylindrical casing, and the preferred form of door is provided with an inclined shoulder 17 and a straight shoulder 18 arranged at an obtuse angle to the inclined shoulder, these two shoulders fitting against 70 correspondingly shaped shoulders formed at the ends of the cylinder, and forming a tight, fluid proof, joint therewith. The shoulder 18 is preferably provided with an annular groove 19 for the reception of a packing ring 75 of rubber or any other suitable material, which, when pressed firmly against the end of the cylindrical wall of the safe will form a joint that will positively prevent the entrance of nitro-glycerin, or other high explosive 80 in the event of the creation of a partial vacuum within the safe, such as is sometimes formed in an attempt at safe blowing.

Projecting from one side of the cylinder to a point beyond the end thereof is a pair of 85 spaced pivot ears 21 that are provided with rectangular openings receiving correspondingly shaped blocks 22 that are guided within the opening, and are free to move in a direction parallel with the axis of the cylindrical body of the safe. Through these 90 blocks passes a pin 23 that extends through a pivot lug 24 projecting from one side of the door 16, the blocks being slidable to permit slight direct movement of the door after the 95 latter has been swung to approximately closed position.

The door is of a diameter exactly equal to the external diameter of the cylindrical casing 10, and is arched to increase its strength. 100 At the center of the door is an opening for the passage of the enlarged portion of a bolt 30, the inner end of which is reduced and threaded at 31 for introduction into the female screw at the end of the bar 14, and the 105 outer end of the bolt has a suitable operating handle 32 by which said bolt may be turned. At the base of the threaded portion 31 is a non-circular shoulder 33 carrying a sleeve or collar 34 that is provided with peripheral notches 35 arranged to receive a slidable locking bolt 36. When the bolt is with-

drawn to the fullest extent, which is determined by the contact of the collar 34 with the inner face of the door, the threaded portion of the bolt rests in an enlarged opening formed in a block 38 that is carried by an inner cover 39 secured to the door, the cover being for the purpose of protecting the lock, bolts and similar portions of the door structure.

10 At a point adjacent to the hinge the door carries a pin 40 which projects beyond the shoulder 17 and is arranged to enter a recess 41 formed in the mating shoulder at the end of the cylindrical casing, and at a diametrically opposite point the casing is provided with a recess 42 for the reception of a 15 slidable locking bolt 43 at the inner face of the door. The two bolts 36 and 43 are provided with enlarged end portions that overlap, and in said end portions are formed 20 openings 44 for the reception of a cam 45 that is rigidly secured to the inner end of a rod 46 extending through the door of the safe and provided at a point outside the latter 25 with an operating handle 47. When this handle is turned, movement is transmitted by the cam to the two bolts tending to move the latter toward and from each other. During the separating movement the bolt 36 enters one or other of the notches 35 of the collar 34, and the bolt 43 is forced into 30 the receiving recess 42. This locks the bolt 30 from rotative movement, and, also, locks the door to the body of the safe. Movement in the opposite direction withdraws 35 both bolts simultaneously and permits turning of the screw and the opening of the door when the screw moves out of the female thread.

40 It will be seen that the screw 30 may be moved entirely out of engagement with the female screw before the door is opened or before the door starts its opening movement, and with the screw in this position the door 45 is pulled outward in order to gain access to the interior of the safe. The construction permits the closing of the door without danger of mutilation of the threads of the screw, such as would occur if the screw projected 50 and started to enter the female screw before the door is fully closed.

The two bolts are guided within a suitable casing formed in part by plates 49 secured to the inner face of the door, and the bolt 36 55 has a notch 50 for the reception of a locking bolt 51 that is under the control of a combination or other lock 52 of any suitable construction, this lock being provided with an operating stem 53 extending through the door 60 and provided with a knob 54. The knob has an annular recess, the inner wall of which is tapered and receives a correspondingly shaped annular flange projecting from the outer face of the door.

65 The door 16', shown at the opposite end of

the body of the safe, is of the same construction as the door 16, with the exception that the straight shoulder 18 is omitted.

In practice it is preferred to place a packing of rubber or other material around the 70 enlarged portion 30 of the bolt stem, said packing being compressed between the base of the operating handle 32 and the front of the safe when the screw is tightened, so that the entrance of an explosive at this point 75 may be prevented.

Having thus described the invention, what is claimed is:—

1. In a safe, a door, a screw having an unthreaded portion extending through an opening formed in said door, and held from lateral play by the wall of said opening, the screw being free to move in the direction of its length to permit full closing movement of the door without turning or engaging the screw, 80 an approximately central bar arranged in the safe and provided with a female thread, a notched collar carried by the screw and serving as a means for preventing outward movement thereof, and means for engaging said 85 collar and locking the same from rotative movement.

2. In a safe, a body portion having a female screw, a door having an opening formed therein, a door tightening screw having an 90 unthreaded portion passing through said opening and held from lateral play by the wall thereof, the screw being free to move in the direction of its length to permit full closing of the door without engaging the tightening 95 screw with the female screw, and means for preventing rotative movement of said tightening screw.

3. In a safe, a door, a screw for forcing the door to closed position, a pair of slideable bars 100 or bolts having recessed end portions, one being movable into engagement with the screw, and the other arranged to enter a locking recess in the wall of the safe, an operating cam entering the recesses, and a han- 110 dled stem carrying said cam.

4. In a safe, a cylindrical body portion open at each end, hinged doors arranged at both ends of the safe, an approximately central bar within the safe, and means carried 115 by the doors for engaging with the opposite ends of the bar.

5. In a safe, a body portion having a partition or cross bar, a bar rigidly secured thereto and having female screws at its opposite 120 ends, hinged doors at the opposite ends of the safe, and threaded bolts carried by the doors and arranged to enter said female screws.

In testimony that I claim the foregoing as my own, I have hereto affixed my signature 125 in the presence of two witnesses:

ADOLPH F. GUSTAFSON.
